UNITED STATES PATENT OFFICE.

FELIX J. TRAINOR, OF NEWCASTLE, INDIANA, ASSIGNOR TO TRAINOR NATIONAL SPRING COMPANY, A CORPORATION OF INDIANA.

AUXILIARY CHASSIS SPRING.

Application filed December 30, 1927. Serial No. 243,584.

This invention relates in general to an auxiliary spring for use in association with the usual semi-elliptic chassis spring as commonly employed in motor vehicles and the like, and relates in particular to the means of mounting and retaining the auxiliary spring in proper relation to the chassis spring.

The invention is herebelow described in one particular form as shown in the accompanying drawing, in which,

Fig. 1, is a side perspective view of my invention mounted on a vehicle frame in an operative position;

Fig. 2, a vertical section on the line 2—2 in Fig. 1; and

Fig. 3, a top plan view of the auxiliary spring hanger.

Like characters of reference indicate like parts throughout the several views in the drawing.

Referring first to Fig. 1 of the drawing, a pair of semi-elliptic springs 10 and 11 are secured to support a vehicle frame 9 in the usual and well known manner. A vehicle is designed to carry a certain load limit, but it is common practice to greatly overload the vehicle, much beyond the load for which the springs were designed to carry, and an auxiliary spring coming into action to care for the overload is desirable.

I form an auxiliary spring hanger, preferably of spring steel to have two vertically positioned spaced-apart legs 13 and 14 and a bar 15 integrally interconnecting the top ends of the legs 13 and 14. The bar 15 is bent over to lie in horizontal plane normal to that of the legs. The legs 13 and 14 and bar 15 are here shown as formed from a single piece of material.

The auxiliary spring hanger is attached one to each side of the frame 9 by placing the legs 13 and 14 against the outer sides of the frame side rails, substantially centrally of the chassis springs 10 and 11, with the bars 15 being uppermost and projecting outwardly from the frame. A bolt 16 is slidingly passed through the lower end of each leg 13 and 14 to extend inwardly under the frame 9 each to receive thereon an anchor bracket 17.

Each anchor bracket 17 has a foot 22 extending back under and along the bolt 16 toward the lower end of the hanger foot, and also has an upper arm 20 extended back over and parallel to the bolt 16 to lie above the

frame rail leg 18 to carry a spring foot 19 which turns sharply upwardly from the outer end of the arm 20 to incline slightly toward the inner side of the frame, so that as the bracket 17 is slipped over the bolt 16 and the nut 21 is drawn up on the bolt, the bracket 17 will be carried toward the frame rail to contact the rail first by the uppermost top of the foot 19 before the lower bracket foot 22 contacts the hanger foot 13, as shown in Fig. 2. Upon continued drawing up of the nut 21, the spring foot 19 will yieldingly turn back to approach a vertical position as the lower foot 22 strikes the hanger foot 13, as indicated by the dash lines in Fig. 2.

In this position, the auxiliary hanger is securely attached to the frame 9, without the necessity of any holes having to be located and bored. The lower bracket foot 22 pushes outwardly on the lower end of the hanger foot to tend to fulcrum the hanger leg over the head of the bolt 16 so as to initially press the upper portion of the leg against the side of the frame, and the frame is actually reinforced by the combined action of the bracket 17 and the legs 13 and 14 through the bolt 16.

Against the under side of each bar 15 are centrally positioned the auxiliary semi-elliptic springs 24 and 26 and there secured by the clips 25. The auxiliary springs are turned with their concave sides toward the main springs 10 and 11, and each auxiliary spring compressively engages the main spring below it by pressing through its free ends upon the blocks 27 which are secured by one end each under the leaf clips 28 to the main springs. These blocks 27 serve not only to prevent wear on the top leaves of the main springs 10 and 11, but by spacing the free ends up from the main springs, aid in securing an initial "no-load" compression against the main springs.

In addition to serving as a relief under main spring overloads, the auxiliary springs 24 and 26 mounted as here shown, also materially aid in checking the objectionable rebound of the main springs by reason of the free ends of the auxiliary springs compressively engaging against the main spring in the initial position.

While I have here shown and described my invention in the form now best known to me, it is obvious that its structure may be varied within the spirit of the invention, and I therefore do not desire to be limited to

this particular form, nor any more than may be necessitated by the following claims.

What I claim is:

1. The combination with a frame side rail of a spring hanger having a vertically disposed leg adapted to contact the outer side of the rail, a bolt passed through the lower end of the leg to lie under the side rail and a bracket carried on the inner end of the bolt, a lower 5 foot extended back under the bolt toward said leg, and an upper foot adapted to elastically contact the inner side of the rail whereby said lower foot may contact the leg upon the yielding of said upper foot.
- 10 2. The combination with a frame side rail of a spring hanger having a horizontally disposed spring attaching bar and a plate vertically disposed from the bar to contact the outer side of the rail and bracket clamping 20 means yieldingly engaging said rail and said plate.

3. The combination with a frame member of a spring hanger having a vertically disposed leg, a member horizontally extended from the lower end of the leg on which the frame rests, and means associated with said horizontal member and the inner side of the frame member whereby the leg is rocked against the outer side of the frame member. 25

4. The combination with a frame member of a spring hanger having a vertically disposed leg, a member horizontally extended from the lower end of the leg on which the frame rests, and means associated with said horizontal member and the inner side of the frame member whereby the leg is rocked against the outer side of the frame member, 30 said means causing the frame member to be yieldingly engaged against said leg. 35

In testimony whereof I affix my signature.

FELIX J. TRAINOR.
